PICTURE FRAME

Petra Cabot and Lidia Vitale, New York, N. Y.

Application August 10, 1948, Serial No. 148,016

Term of patent 3½ years

(Cl. D29—20)

To all whom it may concern:

Be it known that we, Petra Cabot and Lidia Vitale, both citizens of the United States of America, and both residents of New York, in the county and State of New York, have invented the new, original and ornamental Design for Picture Frame, of which the following is a specification, reference being had to the accompanying drawing, forming part thereof, in which:

Fig. 1 is a face view of a picture frame, embodying our new design.

Fig. 2 is an edge view thereof.

Fig. 3 is a sectional view taken on the line 3—3 of Fig. 1.

We claim:

The ornamental design for a picture frame, as shown.

PETRA CABOT.
LIDIA VITALE.
